UNITED STATES PATENT OFFICE.

GEORGE P. FENNER, OF NEW LONDON, CONNECTICUT.

PRINTING-PRESS.

1,150,107.

Specification of Letters Patent.

Patented Aug. 17, 1915.

Application filed August 19, 1914. Serial No. 857,495.

To all whom it may concern:

Be it known that I, GEORGE P. FENNER, a citizen of the United States, residing at New London, county of New London, and State of Connecticut, have invented new and useful Improvements in Printing-Presses, of which the following is a specification.

This invention relates to a printing press in which the rotary impression cylinder can be elevated or lowered at any time by the operator of the press.

One important advantage of this arrangement is that it is possible for the operator to wait until the last instant before the cylinder strikes the form, and even then tripping the cylinder quickly enough to avoid printing on the packing of the cylinder which is the primary reason for throwing off the cylinder. In other words if there is no sheet on the cylinder to be printed the type puts ink on to the packing of the cylinder, hence the following number of sheets will be printed on the reverse side, thus being spoiled.

Another object of the invention is, that none of the tripping devices are in action except when the trip is actually being used, that is: when the cylinder is tripped all the mechanism employed in tripping the cylinder goes out of action. Consequently when the cylinder is lowered or thrown back again the same result occurs. In a press of this kind the mechanism for tripping is manually controlled, there being no cams actuated by the means employed for rotating the cylinder, or moving parts of any sort to complicate the mechanism and wear out.

The elevating and lowering devices are preferably applied to a single revolution printing press in which the impression cylinder revolves once for each impression, while the bed moves forward and back. The cylinder has a raised and depressed periphery so that when the bed moves forward the raised surface of the cylinder engages the form carried by the bed to produce the impression, while at the return stroke of the bed the depressed surface of the cylinder will be out of contact with the bed. In a flat bed press as shown in the drawing the cylinder must have two diameters, the amount of surface which can be used for the impression being approximately about one quarter of the circumference of the cylinder.

The novel features of the invention are more fully described in the following speci-

fication and claims and illustrated in the accompanying drawings in which:

Figure 1 is a plan view of a printing press embodying this invention. Fig. 2 is a side elevation of the same showing the cylinder lowered. Fig. 3 is a front elevation of the same. Fig. 4 is a side elevation of a modification showing the cylinder elevated and tripped.

In these drawings the letter *a* designates a pair of side frames of suitable construction for mounting an impression cylinder *b* and a form carrying bed *c*. The impression cylinder can be revolved and the bed given reciprocating movement in a rectilinear path in any well known way. The mechanism for driving the bed and cylinder is well known and therefore is not shown in the drawing. The cylinder is provided with a raised surface *d* covering about one quarter of the circumference of the cylinder for contact with the form of the bed, and a depressed surface *e* covering the remainder of the cylinder to allow the return stroke of the bed without touching the cylinder. Mounted on the cylinder are a series of grippers *f* which are actuated by the usual cam *g*.

The impression cylinder is provided with a shaft *h* journaled in slides or boxes *i* located at each side of the press and adapted to move vertically in the side frames. A coiled spring *j* coacts with the lower portion of each slide, and these springs support and at the same time have a tendency to push the cylinder upward. Over each slide is connected a toggle lever *k* each toggle having an arm *m* fixed to the upper link of a toggle. A rocker shaft *n* extends across the press between the frames, and it has fulcrumed to it levers *o* located on each side of the press. At each end of a lever *o* is pivoted a link *p* for connection with the ends of the said arms. One of the levers *o* at one side of the press is provided with a connecting rod or pitman *q* preferably pivoted to the link end of the lever and having its lower end connected to a crank *r* mounted on a shaft *s*. This shaft carries a pinion *t* which is adapted to rotate by the actuation of the crank.

The pinion engages a gear *u* mounted on a shaft *v*, as indicated in Fig. 2. The gear *u* is three times the ratio of the pinion. Pivoted to the face of the gear is a pawl *w* which is held in position by a spring *x* secured to the gear. The pawl engages a ratchet *y* fastened to one end of a lever *z*.

To the other end of the lever is pivoted a vertically disposed treadle 10 mounted to slide up and down in a platform 11. By depressing the treadle the full length of its stroke which is permitted by the space between the cap of the treadle and the feeders platform 11 as indicated in Fig. 4, gear *u* will have turned one sixth of a revolution. This revolves the pinion *t* one half of a revolution thereby oscillating the crank and moving the pitman from its downward to its upward position.

It will be seen that it requires one downward motion of the treadle to trip or throw the impression cylinder. When the treadle is not in use as indicated in Fig. 2 and the cylinder is lowered a spring 12 is employed to hold it in its upward position. When in this position the crank *r* is in its lowest position and through the medium of the pitman and its connections it has straightened the toggle levers thus lowering the impression cylinder. When the treadle is again actuated it will swing the crank past the dead center and the spring 12 will restore the treadle to its upward position. While the treadle is moving upward the lever *z* oscillates the ratchet and the pawl engages the next tooth. Attached to the rocker shaft *n* on the opposite side of the press from the operator is an indicating arm 13. When the cylinder is tripped or elevated the indicating arm projects above the feed board 14 as indicated in Fig. 4 and denotes to the operator that the cylinder is elevated and not printing. When the arm 13 is down and out of sight as shown in Fig. 2 it denotes that the impression is on or the cylinder has been lowered to print. Springs 15 and 16 attached to the pitman *q* are adapted to hold the pitman in its correct vertical position. If the treadle 10 is pushed down very quickly the momentum of the pinion *t* may carry the crank beyond its correct vertical position either up or down. The upward position shown in Fig. 4 is not specially important; but the downward position of the crank *r* as shown in Fig. 2, is rather important because the impression depends on the position of the toggle joints. Another method of stopping the crank *r* when in its correct position is shown in Fig. 4. On the outer end of the shaft *s* is a collar having two projecting lugs 17 which coact at predetermined times with an arm 18 forming a continuation of the lever *z*. When the treadle is pressed downward the arm 18 moves into the arc of oscillation or path of one of the lugs. This brings to a positive stop the rotation of the shaft *s* and its pinion thus insuring the correct position of the pitman. To prevent unnecessary shock between the lugs 17 and the arm of the lever a spring 19 is attached to one end of the rock lever *o*. This spring makes it necessary for

the operator to continue the downward stroke of the lever *z* when throwing the impression off, until the rock lever *o* is in its correct upward position. In other words: the spring 19 counteracts to a considerable degree the action of the coiled spring *j* for lifting the cylinder.

Without the spring 19 the cylinder lifting spring *j* may throw the cylinder up unnecessarily fast producing shock between the lug 17 and the arm 18 of the lever. Spring 19 is also for assistance in lowering the cylinder; that is, this spring almost balances spring *j* when the cylinder is in its upward position. When the cylinder is down spring *j* is almost inert. When the cylinder is forced down there is no tendency for this part to go too fast as the spring *j* produces all the required resistance.

With the foregoing arrangement for tripping several important points are gained. The cylinder is at all times under control of the operator, can be tripped at any time, during its revolution, and when the cylinder is elevated or lowered none of the parts are in action thus economizing in wear. It will be seen that the feed board 14 is supported on rails 20 located on each side of the press. One end of each rail is connected at 21 to the gripper cam *g* and the other end is fulcrumed at 22 to the side frames. The cam moves up or down with the journal boxes thus registering with the vertical movement of the cylinder and the grippers. The cam carries with it the rails which swing about the fulcrum to move the board in unison with the cylinder, hence making it possible to feed in perfect register whether the cylinder is elevated or lowered. The feed guides 23 are also swingingly mounted at 24 to a projecting part of the gripper cam. These guides coact with a series of fingers 25 fixed to the under surface of the forward portion of the feed board. By this arrangement the feed board and the feed guide move in unison with the cylinder elevating and lowering means thereby keeping the sheet at all times in perfect alinement with the cylinder.

I claim:

1. In a printing press the combination with an impression cylinder, means for throwing the cylinder, a pinion connected to the throwing means, and a gear of larger diameter connected to the pinion controlled by the operator for tripping the cylinder.

2. In a printing press the combination with an impression cylinder, means for throwing the cylinder, a pinion connected to the throwing means, and a gear of larger diameter in engagement with the pinion controlled by the operator to trip the cylinder.

3. In a printing press the combination with an impression cylinder, means for

throwing the cylinder, a pinion connected to the throwing means, means for limiting the movement of the pinion, and a gear of larger diameter in engagement with the pinion controlled by the operator to trip the cylinder.

4. In a printing press the combination with an impression cylinder, of toggle levers mounted on the axis of the cylinder, means for yieldingly supporting the cylinder, a rock lever connected to the toggle lever, a pitman coacting with the rock lever, and manually controlled tripping devices including gears of different radii connected 15 to the pitman for throwing the cylinder.

5. In a printing press the combination with an impression cylinder, of toggle levers mounted on the axis of the cylinder, means for yieldingly supporting the cylinder, a rock lever connected to the toggle lever, a pitman coacting with the rock lever, a crank pivoted to the pitman, and manually controlled tripping devices including gears of different radii connected to the 25 crank for throwing the cylinder.

6. In a single revolution printing press the combination with a bed, of a rotary impression cylinder in which the impression surface is less than one half the circumference of the cylinder, toggle levers mounted above the axis of the cylinder, means for yieldingly supporting the cylinder, a rock lever linked to the toggle lever, a pitman coacting with the rock lever, a crank pivoted 30 to the pitman, and manually controlled tripping devices connected to the crank for throwing the cylinder, said tripping devices including gears of different diameter for imparting movement to the crank.

40 7. In a printing press the combination with an impression cylinder, of manually controlled means for elevating and lowering the cylinder, a crank coacting with the elevating and lowering means, and tripping devices including gears of different radii for imparting movement to the crank.

8. In a printing press the combination with an impression cylinder, of manually controlled means for elevating and lowering the cylinder at any time, gears of different 50 radii connected to the elevating and lowering devices, a treadle for actuating the gears, and means for preventing excessive movement of the gears.

9. In a printing press the combination 55 with an impression cylinder, of manually controlled means for elevating and lowering the cylinder at any time, a crank and a pinion coacting with the elevating and lowering means, a treadle connected to the 60 crank for actuating the pinion.

10. In a printing press the combination with an impression cylinder, of means including slides for throwing the cylinder, a cam mounted on the slides, and a feed board 65 actuated by the cam.

11. In a printing press the combination with an impression cylinder, of means including slides for throwing the cylinder, a cam mounted on the slides, and a feed board 70 pivotally connected to the cam.

12. In a printing press the combination with an impression cylinder, of means including slides for throwing the cylinder, a cam mounted on the slides, rails pivoted to 75 the cam, and a feed board supported on the rails.

13. In a printing press the combination with an impression cylinder, of means including slides for throwing the cylinder, a 80 cam mounted on the slides, a feed board pivotally connected to the cam, and a feed guide swingingly coacting with the feed board.

In testimony whereof I have hereunto set 85 my hand in the presence of two subscribing witnesses.

GEORGE P. FENNER.
